UNITED STATES PATENT OFFICE

ROY CHALK, OF NEW YORK, N. Y., ASSIGNOR OF ONE-HALF TO MAURICE CHALK, OF NEW YORK, N. Y.

DESIGN FOR AN AMUSEMENT DEVICE

Application filed October 21, 1932. Serial No. 45,444. Term of patent 7 years.

To all whom it may concern:

Be it known that I, Roy CHALK, a citizen of the United States, residing in New York city, (borough of the Bronx), in the county of Bronx, and State of New York, have invented a certain new, original, and ornamental Design for Amusement Devices, of which the following is a specification, reference being had to the accompanying drawing, forming a part thereof, and which is a perspective view of an amusement device showing my new design.

The dice are permanently connected to their supporting members in the positions shown.

I claim:

The ornamental design for an amusement device substantially as shown and described.

ROY CHALK.
